UNITED STATES PATENT OFFICE.

AUGUSTINE P. FAY, OF ROXBURY, MASSACHUSETTS.

BELT-REPLACING DEVICE.

1,250,571.

Specification of Letters Patent. Patented Dec. 18, 1917.

Application filed November 1, 1916. Serial No. 128,832.

To all whom it may concern:

Be it known that I, AUGUSTINE P. FAY, a citizen of the United States, residing at Roxbury, in the county of Suffolk and State of Massachusetts, have invented an Improvement in Belt-Replacing Devices, of which the following is a specification.

In many instances it is a common expedient to slip a belt off of a pulley onto the shaft or counter-shaft bearing the pulley, and to permit it to rest loosely on said shaft, and then to replace it on the pulley when desired for use. In replacing a belt on a pulley while the latter is rotating requires the exercise of considerable skill, and there is much danger attending the operation.

This invention has for its object the construction of an implement especially adapted for this purpose, by which a belt, which is loosely supported on the counter-shaft, may be engaged and placed in engagement with the pulley and there held until it has become correctly arranged on the periphery thereof, the operation being accomplished easily and quickly and without danger.

Figure 1 is a side elevation of a belt-replacing implement employing this invention.

Fig. 2 is a similar view illustrating the device in use.

Fig. 3 is an enlarged view of the device with a side plate removed to uncover the parts concealed by it.

Fig. 4 is an enlarged plan view of the upper end-portion of the device.

Figs. 5 and 6 are detail views of belt-engaging members which may be employed, one adapted for a flat belt and the other for a round belt.

Figs. 7 and 8 are side and bottom plan views, respectively, of another form of belt-engaging member.

Fig. 9 is a detail view of a pulley guide which may be associated with the device.

In the drawings an implement is shown for the purpose of illustrating one embodiment of my invention. 10 represents a pole, which may be hollow and of any desired length, and having one of its end-portions bent or curved in the arc of a circle, as at 12, or otherwise formed, so that its upper end-

portion will extend forward. This pole may be composed of several strips of wood secured together, or in lieu thereof, it may be made of metal. It may be made hollow for the whole or a part of its length. At the extremity of its curved or forwardly projecting end-portion a belt-engaging element is arranged. Said element may consist of a block 15, adapted to support a belt-engaging member on its under side. The belt-engaging member may consist of a plate 18, see Fig. 5, having arranged thereon at one end a boss 19, which is adapted to enter a correspondingly shaped recess, transversely arranged in the under side of the block 15, so that it may be securely held by the block. When the boss is arranged in its recess the plate 18 will be extended laterally from the block 15, as an arm, for a distance equal to the width of a belt to be engaged by it, or a greater distance so that belts of different widths may be engaged. In a simple embodiment of my invention no other means need be arranged on the block 15.

The block and plate supported by it, as here shown, provides an arm extended laterally from a support, which arm is adapted to engage the under side of a belt, but so far as my invention is concerned said belt-engaging element may be otherwise formed to provide a laterally extended arm for engagement with the under side of the belt. Said belt-engaging element is adapted to be connected with the pole in such manner as to be movable relative thereto, yet its connecting means is preferably so constructed as to act to automatically return the belt-engaging element to normal position.

As here shown, the block 15 is connected to one end of a long flexible strip 20, here shown as a flat metallic strip, or in lieu thereof any other form of flexible connection may be employed, and the other end of said strip is connected to one end of the long spiral spring 22, the other end of said spring being connected to a fixed point. Said strip and spring are shown as arranged in the hollow compartment or bore of the pole, at the upper end-portion thereof, and extend downward for a considerable distance, as represented.

sented in Fig. 3. The normal tendency of the spring is to contract and to draw the strip and block attached thereto inward until the block engages the end of the pole, 5 which is its normal position. The block has a shoulder 16, adapted to abut against the end of the pole to thus limit its movement by the spring. The block may have an extension 17 on its end adjacent the pole to 10 which the end of the flexible strip 20 is attached. The arm being laterally extended admits of its engagement with the under side of the belt, by which the belt may be lifted from the counter-shaft to the periphery of the pulley; the flexible strip admits of a movement of the arm bodily with 15 relation to the pole in any desired direction, so that the arm may engage the periphery of the pulley and follow therewith in a circular path, and the spring acts as an elastic means which permits relative movement of the arm and automatically returns the arm to normal position.

When using the implement constructed, as 20 so far described, the person manipulating the same places the projecting portion of the plate 18, or arm, beneath the loosely supported belt and lifts the belt into engagement with the periphery of the rotating pulley, as represented in Fig. 1, resting said plate or arm directly on said periphery, and when in such position, the belt is extended over the top of the plate or arm to hold the plate or arm in engagement with the pulley, 25 whereupon the rotating movement of the pulley is utilized to carry said plate or arm, and block to which it is attached, around with it, the flexible connecting strip 29 bending, and the spring stretching, to admit of such movement of the plate or arm and block, as represented in Fig. 2. As soon as the plate has carried the belt, say one-half of a revolution or thereabout, and when it arrives at that portion of the periphery of 30 the pulley that the belt ordinarily leaves said periphery, the plate or arm will be freed, whereupon the spring will contract and draw inward the flexible strip, and cause the plate, and block to which it is attached, to return 35 to normal position.

The transverse recess in the block 15 extends from side to side thereof, so that the boss 19 on the belt-engaging arm may be thrust inward from either side of the block, 40 and the arm 18 extended laterally therefrom in either direction. In Fig. 5, the arm 18 is adapted for engagement with a flat belt, but in Fig. 6 another form is shown having a curved arm 25 for engagement with 45 a round belt. As the belt-engaging arm is adapted for engagement with the periphery of a pulley and to be held thereon while the belt is being replaced, the arm may have

means arranged on its under side which augment such engagement. In Fig. 5, said arm 55 has projections 30 arranged on its under side adapted to engage a wood or leather-faced pulley. In Fig. 6 the arm may have rubber inserts 31 for engaging a smooth-faced metal pulley.

In lieu of providing for the reversal of the laterally extended belt-engaging arm, a double-armed member may be employed (see Figs. 7 and 8) wherein a plate 40 is shown, having its boss 41 or other attaching-means 45 arranged intermediate its length, so that arms are provided which extend at opposite ways.

There may be associated with said implement, belt-guiding means whereby, when the belt-engaging element is placed in engagement with the under side of the belt, the belt itself, at a point below the pulley, may be received in the guide, and thus guided into position while it is being lifted. As represented in Fig. 1, said belt-guide comprises a pair of arms 50, 50, which are rigidly attached to the pole, at a point below the forwardly extended end-portion thereof, said arms extending forward and being spaced apart sufficiently to receive between them the belt. Said belt-guide 50 may be arranged for detachable connection with a cross-bar 52 arranged on the pole so that it may be connected with either end-portion of the 55 cross-bar.

There may be associated with the implement, a suitable pulley-guide (see Figs. 1 and 9). Said pulley-guide consists of an arm 60, slidably arranged in a recess in a block 61, which has a boss 62 thereon, adapting it to engage the transverse recess in the under side of the block 15, adjacent the belt-engaging element. The arm 60 has at its end a projecting pin 65, adapted to engage the 105 edge of the rim of the pulley. This arm may be adjusted to different sliding positions for pulleys of different widths.

I claim:—

A belt replacing device comprising a pole 110 having a curved end portion, a retractile spring arranged within said pole below the curved end portion thereof and secured, at one end, to said pole, a block removably arranged in the curved end portion of said 115 pole, a lug formed on said block arranged to fit within a socket formed in the curved end of said pole, whereby said block is normally maintained in a predetermined relative engaging position with said pole, means carried by said block arranged to engage a belt, and a flexible strip extended through the curved end portion of said pole and connected to the free end of said retractile spring and said block, whereby said spring serves 120 to normally maintain said block in engage- 125

ment with the end of said pole, and is extended by the bodily movement of said block away from the end of said pole in the operation of replacing a belt, and retracts, subsequent to the belt replacing operation, to replace said block in normal engagement with the end of said pole.

In testimony whereof, I have signed my name to this specification, in the presence of two subscribing witnesses.

AUGUSTINE P. FAY.
